Primary Examiner — S. Bryan Reinholdt, Jr.Assistant Examiner — Jillian Mazzola(74) Attorney, Agent, or Firm — Banner & Witcoff, Ltd.(57) CLAIM

The ornamental design for a bra, as shown and described.

DESCRIPTION

The sole FIGURE is a photographic front perspective view of a bra showing my new design.

The broken lines immediately adjacent the photographic area represent the bounds of the claimed design and form no part thereof. The broken lines showing the remainder of the bra form no part of the claimed design.

1 Claim, 1 Drawing Sheet(56)
